Patented Sept. 3, 1918.

UNITED STATES PATENT OFFICE.

WILLIAM F. MAHONY, OF WASHINGTON, DISTRICT OF COLUMBIA.

WRITING KIT.

1,277,973.

Specification of Letters Patent. Patented Sept. 3, 1918.

Application filed March 23, 1917. Serial No. 156,977.

To all whom it may concern:

Be it known that I, WILLIAM F. MAHONY, a citizen of the United States, residing at Washington, in the District of Columbia, 5 have invented new and useful Improvements in Writing Kits, of which the following is a specification.

This invention relates to writing kits and has as its objects to provide a container or 10 case for writing materials and which may also be employed as a blotter holder and an ink-stand; to provide a compact writing kit of convenient shape so that it may be carried around in the pocket, the construction being such that when not in use, the 15 ink bottle may be located within the case and, when it is desired to use the kit for writing purposes, the bottle may be removed from the interior of the kit and secured to 20 the case in upright position, and when in this position, the bottle may be employed as an ink well and a handle; to provide improved means for mounting the bottle in 25 an upright position; and to provide improved means for removably securing the blotter in position on the container.

The above and other objects of my invention are obtained in the structure described in the following specification and 30 illustrated in the accompanying drawings wherein—

Figure 1 is a perspective view of my improved writing kit.

Fig. 2 is an inside view of the same, the 35 cover being thrown back.

Fig. 3 is a sectional view taken substantially through the longitudinal center of the device.

Fig. 4 is a transverse sectional view taken 40 substantially on line 4—4, Fig. 3.

Fig. 5 is an enlarged view showing in detail the means for clamping the blotter in position upon the bottom of the case.

Referring to the drawings wherein like 45 numerals represent like parts in the several views, 10 designates the body portion of my case; 11 the cover, and 12 the hinge for hingedly connecting the cover to the body portion. The bottom of the body portion 50 and the top of the cover are curved longitudinally toward each other from their central portions to their ends, so that at the center of the case a relatively deep pocket is obtained which is to receive the ink bottle 55 or well. The cover has a rim or wall 13 which engages about the rim or wall 14 of the body portion when the kit is closed, as

is clearly shown in Fig. 4. It is to be understood that the container or case may be constructed of any suitable material, but, preferably, it is formed of sheet metal of light weight.

The end portions of the rim 14 of the body portion 10 are cut-away and to the under surface of the container is secured, 60 by gluing or the like, a pad 15 which is covered or faced with a blotter 16. The ends of the blotter 16 are folded about the ends of the body portion where the wall 14 is cut away, as clearly shown in Fig. 3. 65 Within the case and preferably secured to the front and rear portions of the wall 14 of the body portion are guides 17 which, in the present disclosure, are illustrated as constituting tubes of relatively small diameter, 70 although it is to be understood that they may be formed of strips of metal curved as to form passage-ways. The ends of the tubes 17, as clearly shown in Fig. 5, are 75 slotted or cut away for a portion of their length, as at 18. The clamping members which secure the ends of the blotter comprise U-shaped bails 19, the cross-rods of which extend transversely of the container. The ends of the bails 19 are adapted 80 to slide in the guideways formed by the bores of the tubes 17. The transverse rods of the clamping members 19 are bent outwardly intermediate their ends, as at 20, so as to provide raised portions which may 85 be readily grasped between the fingers when moving the clamping bails into and out of clamping position.

From the arrangement just described, it 90 will be seen that when the blotter on the container has become soiled and it is desired to replace the same with a new one, the clamping bails 19 are moved inwardly toward each other, this being permissible as the tubes 17 are slotted as at 18. In inserting a new blotter, the ends thereof are 95 folded about the ends of the body portion 10 where its walls are cut away, and the clamps are then moved outwardly from each other. As the bails move in a straight line and the ends of the bottom of the body portion are curved and intersect the plane in which the bails reciprocate the blotter is 100 securely clamped in place against the curved ends of the container.

Located in the space centrally of the body portion 10 is a bottle-receiving pocket having an upstanding flange or rim 21, the contour of which corresponds to the configu- 110

ration of the sides of the bottle which it is adapted to engage. In the present instance, I have illustrated the ink-well as consisting of a disk-shaped bottle 22 having a neck 5 portion covered with a cap 23. The rim 21 is in the form of a cylinder of substantially the same diameter as the bottle so that the bottle will snugly fit therein. The rim 21 has a pair of diametrically opposed, projecting spring fingers 24 which receive therebetween and press against the neck portion or the cap 23 of the bottle to hold the bottle against displacement.

Preferably secured to the interior of the 15 cover 11 of the container as by soldering or the like are small flat boxes 25 having lids 26 and in these boxes may be stored stamps, pens, clips, and the like. In the present instance, I have shown two such boxes, and 20 the location of the same is such that, when the cover is folded over the body portion, the bottle-receiving flange 21 will fit in therebetween, as shown in Fig. 3. The boxes 25 and the ink-bottle pocket 21 terminate short 25 of the longitudinal walls 13 and 14 so that spaces are provided along both sides of the ease in which pencils and pen-holders may be placed.

In the top of the cover 11 is provided a 30 transverse elongated opening or slot 27 adapted to receive the ink bottle 22. The width of the slot 27 and the length thereof are substantially equal to the thickness and diameter, respectively, of the bottle, so that 35 the bottle will snugly fit therein.

When it is desired to carry the writing 40 kit in the pocket, the bottle 22 is placed within the chamber 21 and it is held against displacement due to the frictional contact between the edges of the bottle and the rim, and the pressure of the spring fingers 24 against the cap of the bottle. In this condition, the case is relatively flat and compact so that it may be conveniently carried.

45 When it is desired to use the kit as an ink stand, the bottle is removed from its place within the chamber 21 and forced downwardly into the slot or opening 27. To use the device as a blotter, it is merely necessary 50 to grasp the bottle to lift the kit onto the surface to be dried.

It is, of course, obvious that this invention is susceptible of various modifications and changes which would be within the spirit 55 of my invention without departing from the scope of the following claims.

What I claim is:—

1. A container comprising a hollow body portion constructed of sheet metal having an 60 upstanding rim or wall, the end portions of which are cut away, a cover hinged to said body portion, a blotter mounted on said body portion and having its ends inserted in the

cut-away sections of said walls, and slidable means within the container to secure the inserted ends of said blotter. 65

2. A container having a body portion and a cover therefor, the end walls of the body portion being cut-away, a blotter mounted on said body portion and having its ends inserted in the cut-away sections of said walls, and a clamp movable lengthwise of and within said container adapted to engage the blotter ends and clamp them to said body portion. 70

75 3. A container comprising a body portion and a cover therefor, said body portion having its bottom section curved at the ends and its end walls cut-away, a blotter mounted on said body portion with its ends inserted in the cut-away section of said end walls, and a clamp movable lengthwise of and mounted within in said body portion and adapted to clamp the inserted ends of the body against the curving bottom of said body portion. 80

4. A container comprising a body portion and a cover therefor, said body portion having its bottom section curved at the ends and its end walls cut-away, a blotter mounted on said body portion with its ends inserted in the cut-away section of said end walls, guideways on the side walls of said body portion, and a longitudinally movable clamp mounted in said guideways and adapted to clamp the inserted ends of the 95 body against the curving bottom of said body portion.

5. A container having a body portion and a cover therefor, a blotter having its ends folded about the ends of said body portion, 100 tubular guides in said body portion, and a clamping member having its ends extending into said tubular guides, said guides being slotted at their ends to permit reciprocation of said clamping member. 105

6. A container having a body portion provided with a curved bottom, a cover for said body portion, a blotter having its ends folded about the ends of said body portion, guides on said body portion, U-shaped longitudinally movable clamping members having their ends slidably mounted in said guides, said guides being slotted to permit said clamping members to be moved inwardly, and said clamping members being 110 adapted to clamp the ends of the blotter against the curving bottom of said body portion when said members are moved outwardly.

115 In testimony whereof I have hereunto set my hand in presence of two subscribing witnesses.

WILLIAM F. MAHONY.
